Y. HENDERSON,
MASK FOR THE INHALATION OF CARBON DIOXID,
APPLICATION FILED APR. 7, 1920.

UNITED STATES PATENT OFFICE.

YANDELL HENDERSON, OF NEW HAVEN, CONNECTICUT.

MASK FOR THE INHALATION OF CARBON DIOXID.

1,396,429.

Specification of Letters Patent.

Patented Nov. 8, 1921.

Application filed April 7, 1920. Serial No. 371,955.

To all whom it may concern:

Be it known that I, YANDELL HENDERSON, a citizen of the United States, residing at New Haven, in the county of New Haven 5 and State of Connecticut, have invented a new and useful Improvement in Masks for the Inhalation of Carbon Dioxid; and I do hereby declare the following, when taken in connection with the accompanying drawings and the characters of reference marked thereon, to be a full, clear, and exact description of the same, and which said drawings constitute part of this application, and represent, in—

15 Figure 1, a diagrammatic view showing a mask as in use.

Fig. 2, a plan view of the mask.

Fig. 3, a view thereof in side elevation with the mixing-tube partly broken away.

20 My invention relates to an improved mask for the administration of carbon dioxid for the ventilation of the blood in the lungs after the administration of an anesthesia, the object being to provide a simple, convenient, 25 and safe device for the purpose described.

With these ends in view, my invention consists in a mask provided with a mixing-chamber constructed and arranged to waste the gas fed into it during exhalation or 30 cessation of breathing, and to regulate by the volume of breathing, the amount of gas drawn into the mask during inhalation.

My invention further consists in further details of construction as will be hereinafter 35 described and pointed out in the claims.

In carrying out my invention, as herein shown, I employ a mask 2 of ordinary form, made of metal or equivalent material and adapted to fit over the nose and mouth of 40 the patient. In the lower edge of the mask, I locate a flat, rectangular mixing-tube 3, located in the plane of the front of the mask, open at both ends, and projecting into and out of the mask.

45 Within the projecting outer end of the mixing-tube 3, I locate the perforated inner end of a feed-tube 4, arranged at a right angle to the said mixing-tube and having its inner end closed, while its projecting outer end is formed with corrugations 5 for the application of one end of a rubber gas-supply tube 6. That portion of the feed-tube located within the mixing-tube, is formed in its lower or outer face with a 50 series of minute perforations 7 which, as shown by Fig. 3, face outwardly, as it were,

from the mask. The size and number of the perforations 7 will be determined according to requirements. The gas, as it issues from the perforations 7 either wastes 60 into the air or is drawn with the air into the mixing-tube, the inner portion of which forms a mixing-chamber 8 in which the gas and air are commingled before being drawn into the body of the mask. 65

The gas-supply tube 6 has its outer end connected through the medium of an ordinary capillary, which is not shown, but which is located at the point 9, with the limb 10 of a T tube connected by a reducing-valve 11 with a tank 12 of carbon dioxid of the best beverage quality. The branch 13 of the T tube aforesaid, is immersed in a vessel 14 of water serving both as a gage and as an escape-valve to prevent any excessive 70 pressure on the capillary. I am thus enabled to control the amount of carbon dioxid supplied under the maximum pressure to the mask.

Supposing the device to be in use, it depends upon the patient's own breathing to draw the minute quantities of gas expelled under pressure from the perforations in the feed-tube 6, inward around the tube 4 into the mixing-chamber 8 of the mixing-tube, 85 from which it is drawn into the mask and inhaled. During exhalation or cessation of breathing, the gas merely wastes into the outside air; during inspiration, it mixes with the inspired air, as described. The operator controls the administration according to the reactions of the patient who receives approximately one-half of the gas which the apparatus measures off per minute. The percentage of carbon dioxid in the inspired 90 air, therefore, depends upon the volume of breathing, and the administration will be controlled accordingly. 95

What I particularly wish to emphasize is that by constructing my improved mask so 100 as to waste the gas during expiration or cessation of breathing, and to utilize it under control only during inspiration, when the amount inspired will depend upon the volume of breathing, I provide the maximum 105 of safety in the administration of the gas.

The beneficial effects observed are (a) an augmentation of breathing which rapidly ventilates the anesthetic out of the blood in the lungs, (b) markedly less post-operative 110 nausea and vomiting, (c) a powerful stimulant effect upon the circulation without sub-

sequent relapse or unfavorable consequences, (d) a possible restoration of intestinal tonus.

I claim:

- 5 1. A mask for the administration of carbon dioxide for the ventilation of the blood in the lungs, the said mask having a mixing-chamber opening into its interior and into the atmosphere and the said mixing-chamber containing a gas-distributer formed with 10 openings positioned to waste the gas during expiration or cessation of breathing and to permit the gas to be drawn into the mask, mixed with outside air, during inspiration.
- 15 2. A mask for the administration of carbon dioxide for the ventilation of the blood in the lungs, the said mask having a mixing-chamber opening into its interior and also into the atmosphere, and the said mixing-chamber receiving a feed-tube provided with 20 a plurality of minute perforations positioned to waste the gas during expiration or cessation of breathing and to permit the gas to be drawn into the mask, mixed with outside air, during inspiration.
- 25 3. A mask for the administration of carbon dioxide for the ventilation of the blood in the lungs, the said mask having mounted in it a mixing-tube opening at its inner end

into the interior of the mask and opening at its outer end into the atmosphere, and receiving a feed-tube having minute perforations positioned with respect to the intake of the mixing-tube to waste the gas during expiration or cessation of breathing and to permit the gas to be drawn into the mask, mixed 30 with outside air, during inspiration.

4. A mask for the administration of carbon dioxide for the ventilation of the blood in the lungs, the said mask having mounted in it a mixing-tube opening into its exterior 35 and also into the atmosphere, and the said mixing-tube receiving a feed-tube mounted in its projecting end at a right angle thereto and formed with a plurality of minute outwardly opening perforations, whereby the 40 gas wastes into the outer air during expiration or cessation of breathing and is drawn into the mask, mixed with outside air, during inspiration.

In testimony whereof, I have signed this 45 specification in the presence of two subscribing witnesses.

YANDELL HENDERSON.
